UNDERWATER SPARK DISCHARGE SOUND-
PRODUCING SYSTEM

Wayne A. Kearsley, Chelmsford, Louis Lucas, Jr., Cambridge, and Donald E. Watts, Belmont, Mass., assignors to Edgerton, Germeshausen & Grier, Inc., Bedford, Mass., a corporation of Massachusetts

Filed Jan. 18, 1965, Ser. No. 426,242

11 Claims. (Cl. 340—12)

This invention relates to underwater sound-producing systems and more particularly to underwater electro-acoustical systems in which pulses of electrical energy are suddenly discharged into a transducer to generate sound pulses.

Sound waves have been used extensively in such underwater activities as surveying the ocean floor and sub floor, tracking moving bodies, navigation and searching for lost wrecks. A number of different sound sources have been used including explosives, propane gas guns, pulsed crystal transducers, magnetostrictive transducers and electric-discharge spark gaps. It is within the field of spark gaps that this invention resides.

Underwater spark-producing sound sources have a pair of spaced electrodes disposed at the end of a towing cable. Pulses of electrical energy are discharged across the electrodes and through the water therebetween. The arc discharge thus created, generates sound waves whose characteristics are a function of the spark gap design and the electrical energy discharged therein. Such sparking devices may be divided into two classes which depend upon the location of the ground electrode. In the merged-type of spark gap, the second or ground electrode is disposed sufficiently close to the first or high-voltage electrode, that the plasma bubble formed at the first electrode in response to the pulses of electrical energy, will extend to the second electrode before it collapses and a direct flow of current through the plasma from the first to the second electrode takes place. In such a system, a special low-inductance circuit is required for impedance matching because the plasma itself has such a low resistance. The second or unmerged class of sparkers positions the ground electrode beyond the maximum expansion region of the plasma bubble. In this class, the electrical current flowing in the discharge arc must pass through the water outside the bubble in route to the second electrode. A substantial energy factor is wasted by the current flow through water. This reduced efficiency has been a serious disadvantage in unmerged sparkers.

Other disadvantages which have been common in underwater sparkers of both classes include short life, low intensity output, and poor frequency control.

It is, therefore, an object of this invention to provide a new spark-discharge underwater sound source which is not subject to the above-mentioned disadvantages.

Another object is to provide a new and highly-efficient underwater sound system which maximizes the output intensity at the most desirable frequencies.

A further object is to provide a new high-voltage electrode assembly.

Still another object is to provide a system in which a plurality of spark discharge devices are arranged to amplify the acoustical energy output.

Other and further objects will be hereinafter pointed out in the following specifications and in the appended claims. In summary, our invention resides in an underwater sound source of the unmerged sparker type in which a high-voltage electrode is spaced from a second electrode by a distance slightly greater than the radius of the plasma bubble produced by energization of the first electrode. The high-voltage electrode itself is a special unit having a central conductive member and an outer insulator, the

2

materials and dimensions of which have been selected for optimum performance and for maximum life. Preferred electrical and constructional details are hereinafter set forth.

5 Our invention will be better understood by referring to the attached drawings in which:

FIGURE 1 is a perspective view partly in schematic form of a typical prior art underwater spark discharge device;

10 FIGURE 2 is a sectional view of a simple embodiment of our invention;

FIGURE 3 is a sectional view of a novel high-voltage electrode assembly;

15 FIGURE 4 is a perspective view of a preferred embodiment of our invention in which plurality of spark discharge devices are arranged in an array; and

FIGURE 5 is a graph of the relative amplitude-frequency curves for pulses of different voltages and

20 FIGURE 6 is an electrical schematic diagram of one embodiment of the present invention.

FIGURE 1 shows a prior art spark-discharge device of the unmerged type having an elongated high-voltage electrode 10 covered except at one end by insulator 15, which may be an insulative tape or the like. A second electrode

25 19, normally at ground potential, is disposed remote from the exposed end of high-voltage electrode 10. The distance between electrode 19 and the exposed end of electrode 10 is predetermined to insure that the former is beyond the limits of maximum expansion of the plasma bubble formed about the tip of electrode 10 during discharge to avoid the impedance matching problem mentioned above. The maximum expansion of the plasma bubble may be determined experimentally by high-speed photographic techniques, an example of which is reported

30 by Edward A. Martin in an article entitled, "Experimental Investigation of a High-Energy Density, High-Pressure Arc Plasma," in the February 1960 issue of the Journal of Applied Physics, volume 31, number 2. By covering the greater portion of electrode 10 with insulation 15 and

35 leaving only a small portion exposed to sea water, the current emitted from electrode 10 is concentrated at its exposed end thus creating a high current density at the end of the electrode when high energy pulses are discharged therethrough. Electrodes 10 and 19 are connected across a high-energy source, such as illustrated in

40 FIGURE 6, by coaxial cable 13. When a high-energy pulse is fed from such a source to electrode 10, a plasma bubble is quickly formed at the exposed end of the electrode and it very rapidly expands to a maximum size which

45 is a function of the energy discharged and the configuration of the sparker assembly. The bubble is formed through ohmic heating of the sea water into steam and it expands very rapidly while the discharge pulse is rising. The size of the bubble is a function of the discharge energy

50 and the current density in the discharge path. No bubble is formed at electrode 19 because the current density there is not great enough to convert the water into steam. As the discharge energy enlarges the plasma bubble, it approaches a maximum size which is shown by the dotted

55 line in the figure enclosing the "Useful Energy Region." The useful sound waves produced by electrical discharge through a sparker are created during the initial expansion of the plasma bubble. The size of the bubble and the instantaneous velocity of its expansion are important factors in the characteristics of the sound emitted. The discharge energy expended within this region, creating the

60 bubble, contributes to the sound produced, but all the electrical energy expended outside this region is wasted. The current which flows through the plasma, must also pass through the regions of sea water, outside the bubble, en route to electrode 19. This current flow is shown schematically as lines 11 in the figure. The greater the

separation distance between electrodes 10 and 19, the longer the current path through the water and thus, the more energy that is wasted.

FIGURE 2 shows an embodiment of the applicants' invention which is simple in structure and highly efficient in operation. A high-voltage electrode 10 is centrally disposed within an insulating member 15 with electrical coaxial connector 13 providing means for energizing electrode 10. The ground electrode 20 is a cage-like element, for example, cylindrical meshwork with electrode 10 disposed substantial along the axis of the cylinder. The distance separating the mesh of electrode 20 from the exposed end of electrode 10 is the radius of the cylinder and is predetermined experimentally by high-speed photographic techniques to insure that it is slightly greater than the "Useful Energy Region" shown in FIGURE 1, which is the maximum size of the plasma bubble produced by the discharge of energy through the terminal portion of electrode 10. Electrode 20 must have a high percentage of open area because the primary purpose of the spark discharge device is to emit acoustical energy and a closed electrode would greatly attenuate the sound. The mesh-work of electrode 20 is designed to pass substantially all the acoustical energy generated during the creation of the plasma bubble, and to provide an effective ground electrode just outside the bubble at its maximum expansion. By so positioning electrode 20, current flows only a short distance through sea water between the bubble and electrode 20, thus assuring that most of the discharge energy is used in forming the bubble and very little is wasted in the water outside the bubble. Although electrode 20 is shown as a cylindrical cage, it may be constructed in other configurations. The cylindrical cage is preferred because it maintains the electrodes 10 and 20 parallel for advantages explained hereinafter.

FIGURE 3 shows a new electrode assembly 25 which has greatly extended the life of sparker electrodes. The high voltage electrode 10 is an elongated rod of a conductive metal such as, for example, brass. An insulator 15 is coated thereupon or molded thereto. Preferably, the insulative material is a molded neoprene jacket but other high-impact strength insulators such as, for example, polyurethane, nylon, epoxy resins, and the like may be used as long as they have good bonding properties.

It is well known that high-voltage electrodes operated in a salt water environment, will erode or disintegrate at a predictable rate controlled by the energy in the discharge and the number of discharges. It has been pointed out above that it is important to cover all of the high-voltage electrode except a small surface area in order to concentrate current flow the small area and thereby produce a high current density to create the plasma bubble. If the insulation 15 covering electrode 10 is very thin, then it is most probable that it will crack, break and fall off because of the high-power discharges and in so disintegrating, an increasing area of the surface of electrode 10 is exposed thereby lowering the current density until it no longer creates a plasma bubble. If on the other hand, insulation 15 is too thick, it will remain in place as electrode 10 erodes therein. In this case, the length of the discharge path increases as the exposed end of electrode 10 recedes into insulation 15 until the path becomes too great to support the discharge at which time the device becomes inoperative.

We have discovered that there is a range of thicknesses for insulator 15 which avoids both the foregoing problems because the insulation disintegrates at substantially the same rate that electrode 10 does. For the class of insulators mentioned above, we have found that the best results are obtained when the thickness of insulator 15 is approximately equal to the radius of electrode 10. The insulator may, however, have a diameter within the range of 1½ to 3 times the diameter of electrode 10, more or less. By so controlling the dimensions, substantially uni-

form disintegration of electrode 10 and insulator 15 is attained, thus prolonging the useful life of the assembly 25, and maintaining the above exposed small surface area substantially constant as disintegration proceeds.

5 A waterproof electrical plug 17 is disposed at one end of electrode assembly 25 for holding assembly 25 in position and providing electrical connection thereto. Plug 17 is made from an insulative material and preferably from the same material as insulator 15, thus permitting the entire assembly 25 to be formed in a single operation by molding insulator 15 and plug 17 onto electrode 10. A raised portion 18 is provided on plug 17 to maintain the assembly securely in its socket.

An important feature of electrode assembly 25 and particularly of plug 17 is that these assemblies may be easily removed and replaced in a minimum of time. Previously, sealed joints were employed for this purpose and it was necessary to cut them open and remove a connecting bolt before a new electrode assembly could be inserted. This 10 was a time-consuming operation which disabled the entire system while it was performed.

As an example, an electrode assembly 25 was made using a $\frac{3}{16}$ inch diameter brass electrode 10, about which a $\frac{3}{8}$ inch diameter neoprene jacket was molded. The 15 useful length of the assembly was 12 inches from plug 17 to the exposed tip. Such an assembly was used in the system shown in FIGURE 4 where 2,000 joules from a 4 kv. source was discharged and the life of the electrode was excellent. A number of assemblies so tested produced over 100,000 discharges at this power level.

It has been found that there is an optimum operating voltage for spark discharge devices. FIGURE 5 shows a graph of two curves indicating the frequency response from discharges of capacitors charged to different voltage 20 levels. Curve A represents a 4 kv. pulse and it may be noted that the flat top of the curve is found in the low-frequency region in the vicinity of 100 c.p.s. which has been found to be the most desirable operating frequency for underwater seismic surveying. At 100 c.p.s. greater penetration of the ocean bottom is realized, thus, increasing the total results from seismic surveying. Curve B in FIGURE 5 demonstrates a higher acoustical output from pulses of 10 to 20 kv. This increased acoustical output is shifted into the higher frequency ranges than that 25 produced by a 4 kv. discharge, indicated as curve A. Although curve B demonstrates greater relative amplitude in the output, the shift of the curve to the undesirable higher frequencies more than offsets the increase in amplitude. The optimum operating conditions for a spark-discharge device is, therefore, a pulse in the 4 kv. range from a high-capacity energy-storage capacitor.

A power supply suitable for operating the system of FIGURE 2, or one of the assemblies 25 in FIGURE 4, is illustrated in FIGURE 2 of U.S. Letters Patent 2,478,556, issued on August 16, 1949 to H. E. Edgerton and now assigned to the assignee of the present invention. The circuit of FIGURE 2, suitably modified, is illustrated schematically in FIGURE 6. Power supply 31 is adapted to charge capacitor 32 to a high voltage potential such as the above discussed 4 kv. Capacitor 32 is connected in series circuit with main electrodes 34 and 35 of triggered spark gap 37 which has trigger electrode 36 and with electrodes 10 and 20 of an assembly such as illustrated in FIGURE 2. Trigger circuit 33 connects across trigger electrode 36 and main electrode 34 of triggered spark gap 37. When trigger circuit 33 is operated a sufficiently high voltage is impressed across main electrode 34 and trigger electrode 36 to cause the gas in triggered spark gap 37 to ionize. The high voltage potential on capacitor 32 is sufficiently high to cause breakdown to occur between main electrodes 34 and 35 and capacitor 32 then discharges between electrodes 10 and 20, causing a plasma bubble to form and generating an acoustical 60 pulse. It will be clear to those skilled in the art that a

single trigger circuit 33 can be utilized to discharge a number of charge capacitors 32 into their associated transducers.

Due to the fact that the most desirable acoustical signal is generated from approximately a 4 kv. pulse, the means for increasing the amplitude of the output signal in the frequency range desired is not increased voltage but rather the simultaneous firing of a plurality of such devices. An apparatus embodying this principle is shown in FIGURE 4. Three electrode assemblies 25 are linearly positioned equidistant from parallel metallic supports 20 which act as the ground electrode in the discharge system. The supporting structure is shown as a triangular frame whose members are an electrically conductive metal such as stainless steel. Cross members 27 provide structural strength and arms 28 welded to the cross members 27 clamp the electrical socket 30 for each electrode assembly 25 securely in place. Each electrode assembly 25 is connected by a different cable 13 to a single cable 29 and in turn to sources of energy, usually capacitors, through a common switch, thus providing simultaneous firing of the electrode assemblies 25.

In addition to triangular frames, other configurations may also be used, such as the cylindrical cage shown in FIGURE 2, rectilinear shapes, etc. The important consideration is that the side members 20 be disposed parallel to the electrode assembly 25 and the minimum spacing be slightly greater than the maximum expansion of the bubble.

For the purposes pointed out above, the electrode assemblies 25 and the triangular support structure 20 are maintained parallel and electrode 10 is substantially equidistant from the structural members 20. As the system is operated, the high-voltage electrode 10 and the insulator 15 will erode at a substantially constant rate. In so doing, the parallel structure maintains the predetermined distance which is important for the operation of the system as pointed out above.

A four-wire cable 29, with one wire 13 for each electrode assembly 25 and a common ground lead, is covered with neoprene to provide both the electrical energy and the towing means to the system shown in FIGURE 4. The plug-in electrode assemblies 25 may be removed and replaced in less than a minute which is a great advantage in minimizing the time lost in this operation. In our preferred embodiment, we have shown three electrode assemblies 25 but more or less may be used depending upon the task to be performed. This three electrode array is a convenient size which is easily handled and yet produces high amplitude sound pulses in the optimum frequency region. Such an array, constructed of stainless steel may be 79 inches long and 10 inches on each side with a total weight of 28 pounds. Input energy may vary from 500 to 7500 joules per pulse and it may be fired as fast as the electrical system can be recharged and triggered, usually about 4 pulses per second at 500 joules.

Although we have shown and discussed our invention in terms of its preferred embodiment, it has considerably greater scope as will be obvious to those skilled in this art and to whom all such modifications will be apparent and all such are deemed to fall within the spirit and scope of our invention.

We claim:

1. An underwater sound-producing system comprising: an insulated electrode having a small area exposed to the water;

an uninsulated electrode disposed a predetermined distance from said insulated electrode; and high-voltage potential means connected across said electrodes and adapted to discharge from the small exposed area of said insulated electrode to said uninsulated electrode, said discharge causing a plasma bubble to form about said exposed area, said pre-

determined distance being just greater than the maximum expansion of said plasma bubble.

2. An underwater sound-producing system as in claim 1 in which said uninsulated electrode is a sound-passing structure disposed said predetermined distance from said exposed area.

3. An underwater sound-producing system as in claim 2 in which said insulated electrode comprises an elongated, conductive metal rod, said metal rod and insulation being designed to have the same rate of disintegration during operation so as to maintain substantially constant said small exposed area.

4. An underwater sound-producing system comprising: an uninsulated electrode; an insulated electrode having a small area exposed to the water and disposed a predetermined distance from said uninsulated electrode, said electrode and its insulation being designed to have the same rate of disintegration during operation so as to maintain substantially constant said small exposed area; supporting means maintaining said electrodes at said predetermined distance; and

high-voltage potential means including a capacitor charge to a high voltage connected to said electrodes and adapted to discharge said capacitor through the water between said electrodes to form a plasma bubble therebetween, said predetermined distance being just greater than the maximum expansion of said plasma bubble.

5. An underwater sound-producing system comprising: an uninsulated electrode having a plurality of parallel, conductive, rod-shaped members disposed an equal distance from a central axis;

a rod-shaped electrode disposed along said central axis and so insulated as to present a small exposed area at one end to the water, said electrode and insulation being designed to have the same rate of disintegration during operation so as to maintain substantially constant said small exposed area;

supporting means maintaining said electrodes at said equal distance; and

high-voltage potential means connected to said electrodes and adapted to discharge a capacitor charged to a high voltage through the water between said electrodes forming a plasma bubble therebetween and producing an acoustical pulse, said equal distance being just greater than the maximum radius of said plasma bubble.

6. An underwater sound-producing system as in claim 5 in which said capacitor is charged to a high voltage potential of about 4 kv.

7. An underwater sound-producing system comprising: an uninsulated electrode comprising a cylindrically shaped wire mesh having a central axis;

a rod-shaped electrode disposed along said central axis and so insulated as to present a small exposed area at one end to the water, said electrode and insulation being designed to have the same rate of disintegration during operation so as to maintain substantially constant said small exposed area;

supporting means for maintaining said electrodes fixed in position with respect to each other; and

high-voltage potential means connected to said electrodes and adapted to discharge a capacitor charged to a high voltage potential through the water between said electrodes forming a plasma bubble therebetween and producing an acoustical pulse.

8. An underwater sound-producing system as in claim 7 in which the inner diameter of said uninsulated electrode is just greater than the maximum expansion of said plasma bubble.

9. An underwater sound-producing system comprising: a plurality of insulation-covered electrodes each having a small area exposed to the water;

an uninsulated electrode disposed a predetermined distance from said electrodes; and high-voltage potential means connected across said uninsulated electrode to each of said insulated electrodes and adapted to discharge from the small exposed area of each of said insulated electrodes to said uninsulated electrode, said discharge causing a plasma bubble to form about each said exposed area, said predetermined distance being just greater than the maximum expansion of said plasma bubbles.

10. An underwater sound-producing system comprising: a plurality of elongated, insulation-covered electrodes each having a small area exposed to the water; an uninsulated electrode frame; means for mounting said insulation-covered electrodes within but spaced a predetermined distance from said frame; and high-voltage potential means connected across said uninsulated electrode frame to each of said insulation-covered electrodes and adapted to discharge from the small exposed area of each of said insulation-covered electrodes to said uninsulated electrode frame, said discharge causing a plasma bubble to form about each said exposed area, said predetermined distance being just greater than the maximum expansion of said plasma bubbles.

mined distance being just greater than the maximum expansion of said plasma bubbles.

11. An underwater sound-producing system as in claim 10 in which said high-voltage potential means includes a high-capacity, energy-storage capacitor charged to a high-voltage potential of about 4 kv.
